UNITED STATES PATENT OFFICE

129,150

DESIGN FOR AN ANIMATED DISPLAY
DEVICE

Aubrey B. Leech, Los Angeles, Calif.

Application November 27, 1940, Serial No. 96,872

Term of patent 3½ years

To all whom it may concern:

Be it known that I, Aubrey B. Leech, a citizen of the United States of America, residing at Los Angeles, in the county of Los Angeles, State of California, have invented a new, original, and Ornamental Design for an Animated Display Device, of which the following is a specification, reference being had to the accompanying drawing, forming a part thereof.

Fig. 1 is a front elevational view of the animated display device showing my new design and the appearance thereof when the same is illuminated from within.

Fig. 2 is a side elevational view of the device with the protective housing shown in Fig. 5 removed, showing the electric lamp supporting base and the cylindrical rotating screen.

Fig. 3 is a sectional view in front elevation of the device taken on the line 3—3 of Fig. 2, showing the intermediate plate which cooperates with the rotating screen to animate the painting on the forward plate of the device.

Fig. 4 is a top plan view of the device showing the fins on the top of the rotating screen which cause the screen to rotate in response to the

warm air currents passing upwardly therethrough from the lamp.

Fig. 5 is a side elevational view of the device shown on a smaller scale with the protective housing in place.

The stippling shown in Figs. 2 and 3 indicates portions of the rotor and plate which are relatively opaque with respect to the balance of the rotor and plate respectively.

The picture shown in Fig. 1 is in contrasting colors, and is so correlated with the plate and rotor that when the rotating screen is illuminated and rotated, there is produced the impression of a stream of golden colored liquid pouring down upon the puffed grain illustrated in the lower portion of the picture, with the effect of turbulence about the grain. In the design shown, some puffed grain is retained in the lower portion of the space immediately in front of the painted plate shown in Fig. 1.

I claim:

The ornamental design for an animated display device, as shown and described.

AUBREY B. LEECH.
